No. 36,459.

Patented July 21, 1903.

UNITED STATES PATENT OFFICE.

FREDERICK T. BROSI, OF QUINCY, ILLINOIS.

DESIGN FOR A COAL-HOD.

SPECIFICATION forming part of Design No. 36,459, dated July 21, 1903.

Application filed May 11, 1903. Serial No. 156,717. Term of patent 3½ years.

To all whom it may concern:

Be it known that I, FREDERICK T. BROSI, a citizen of the United States, residing at Quincy, in the county of Adams and State of Illinois, have invented a new, original, and ornamental Design for a Coal-Hod, of which the following is a specification.

This invention relates to a new, original, and ornamental design for a coal-hod, as shown in the accompanying illustration, in which is represented a perspective view of a coal-hod, showing this new and ornamental design.

I claim as my invention—

The ornamental design for a coal-hod as shown in the accompanying drawing.

In testimony that I claim the foregoing as my own I have hereto affixed my signature in the presence of two witnesses.

FRED. T. BROSI.
